PROCESS FOR PREPARING PYRIDINE CARBOXYLIC ACIDS

Andrew J. Martin, East Orange, N. J., assignor to Allied Chemical & Dye Corporation, New York, N. Y., a corporation of New York

No Drawing. Application March 26, 1952,
Serial No. 278,746

11 Claims. (Cl. 260—295.5)

This invention relates to a process for the oxidation to pyridine carboxylic acids of heterocyclic aromatic nitrogen compounds containing a single pyridine nucleus and having at least one oxidizable hydrocarbon group, attached to the pyridine nucleus by at least one carbon-to-carbon linkage, and more particularly to the production of nicotinic acid from certain compounds of this type.

Pyridine carboxylic acids are useful as intermediates in various organic reactions and in the pharmaceutical field. Of these acids, 3-pyridine carboxylic acid, i. e. nicotinic acid (Niacin) is a member of the vitamin B complex group and is useful in the enrichment of foods to improve their nutritional values.

Substituted pyridine and quinoline type compounds of the character described have been oxidized in the past to pyridine carboxylic acids by a number of methods including oxidation with sulfuric acid at high temperatures in the presence of a catalyst. Such oxidations, using sulfuric acid as the sole oxidizing agent, are usually carried out at temperatures between about 305° C. and about 325° C. and even at these temperatures and with catalytic acid require considerable time for completion of the oxidation reaction, usually from about 6 to about 24 hours in the presence of a selenium catalyst.

Efforts to provide processes which could be carried out at lower temperatures and/or in shorter times, have resulted in the use, for example, of nitric acid or perchloric acid as oxidizing agents in sulfuric acid medium with or without catalysts. These processes, while satisfactory from the point of view of rapidity and lower temperature operation, nevertheless, require the use and handling of liquid oxidizing agents which are expensive and which from time to time are in short supply.

I have now found that pyridine carboxylic acids may be prepared rapidly, in good yields, at low temperatures, without resort to auxiliary liquid oxidizing agents, according to my invention wherein heterocyclic nitrogen compounds containing a single pyridine nucleus and having at least one oxidizable hydrocarbon group attached to the pyridine nucleus by at least one carbon-to-carbon linkage are oxidized in the liquid phase to pyridine carboxylic acids by concentrated sulfuric acid aided by gaseous nitrosyl chloride as an auxiliary oxidizing agent.

As examples of such compounds susceptible to oxidation by the process of the present invention there may be mentioned quinoline, isoquinoline, the picolines or methyl pyridines, such as 2-picoline, 3-picoline and 4-picoline, the lutidines or dimethyl pyridines, the collidines, for example γ -collidine or trimethyl pyridine and aldehyde collidine or 2-methyl-5-ethyl pyridine, as well as the methyl quinolines, methyl isoquinolines, 5- and 8-nitroquinolines, 5- and 8-hydroxy quinolines, etc.

If the heterocyclic aromatic nitrogen compound of the character described has an oxidizable hydrocarbon substituent attached to the pyridine nucleus in one beta position only, has no unoxidizable substituent group on the pyridine nucleus and has not more than two additional oxidizable substituents on the pyridine nucleus each of which is in an alpha position, its oxidation will produce nicotinic acid, either directly in the case of compounds having a single beta substituent such as 3-picoline, or indirectly in the case of poly substituted compounds by oxidation of all the substituents followed by decarboxylation of all but a single beta carboxylic acid group.

I have found that gaseous nitrosyl chloride (NOCl) which is an inexpensive waste material available in large

2

quantities as a by-product of chlorine manufacture, when introduced into a sulfuric acid solution of a heterocyclic nitrogen compound of the character described, at oxidation temperatures, either in the absence of a catalyst or in the presence of a catalyst such as a selenium-containing catalyst, acts as an auxiliary oxidizing agent, markedly to accelerate the rate of the sulfuric acid oxidation. Under certain conditions its action is that of a "supplementary oxidizing agent" which term, when used herein, means that when such agent is used in conjunction with sulfuric acid in the oxidation of a heterocyclic nitrogen compound, there results a higher rate of oxidation than is obtained by the use of sulfuric acid alone under otherwise identical conditions, but a rate not higher than the additive oxidation rate attributable to both sulfuric acid and the auxiliary oxidizing agent combined. Under certain other conditions the nitrosyl chloride acts as a "promoter," which term, when used herein, means that the auxiliary oxidizing agent, when used in conjunction with sulfuric acid in the oxidation of a heterocyclic nitrogen compound, results in a higher rate of oxidation than the additive oxidation rate attributable to both sulfuric acid and the added oxidizing agent combined. The term "auxiliary oxidizing agent" is used herein as a generic term to denote both supplementary oxidizing agents and promoters; and "auxiliary oxidizing action" is used to denote the production of any increase, however small or large, in the oxidation rate over that produced by sulfuric acid alone and includes both supplementary oxidizing action and promoter action.

An auxiliary oxidizing effect on the sulfuric acid oxidation of heterocyclic nitrogen compounds is exerted by nitrosyl chloride in either the presence or the absence of a catalyst. Sulfuric acid alone, in the absence of a catalyst, produces virtually no conversion of heterocyclic nitrogen compounds to pyridine carboxylic acids, even when heated at elevated temperatures of the order of 300° C. for prolonged periods of 10 hours or more. With the aid of a selenium type catalyst, complete conversions to pyridine carboxylic acids by sulfuric acid alone require periods ranging between about 6 and about 24 hours. Using nitrosyl chloride as an auxiliary oxidizing agent according to the process of my invention and carrying out the oxidation at temperatures between about 240° C. and about 300° C., complete conversions may be obtained in the presence of a catalyst such as a selenium catalyst, in periods varying between about 30 minutes and about 2 hours depending on the temperature and rate of nitrosyl chloride input and the particular heterocyclic nitrogen compound oxidized.

In carrying out the process according to my invention, the heterocyclic aromatic nitrogen base compound, dissolved in concentrated sulfuric acid, is subjected to the action of nitrosyl chloride at elevated temperatures in the presence or absence of a catalyst. In a preferred method of carrying out the process, the heterocyclic aromatic nitrogen base compound is mixed with sufficient concentrated sulfuric acid to provide at least a slight excess thereof over that required to form the nitrogen base sulfate and to maintain such an excess during the oxidation reaction. A catalyst such as selenium or a selenium compound is added to the charge and, after bringing the charge to oxidizing temperature, the gaseous NOCl auxiliary oxidizing agent is passed into the hot solution. Flow rate of NOCl may be controlled to provide the optimum or desired supplementary or promoter oxidizing action at the particular oxidizing temperature and the oxidation is continued until the desired conversion of heterocyclic nitrogen compound is attained.

Quantities of catalyst, such as selenium or selenium compound catalyst, used may be between about .5% and about 25% based on the weight of the heterocyclic nitrogen compound used. The sulfuric acid used is concentrated sulfuric acid, i. e. from about 95% to 100%, the ordinary "concentrated" sulfuric acid of commerce (95-96%) being satisfactory.

The temperatures at which the oxidation of the heterocyclic nitrogen compounds described may be carried out using the gaseous nitrosyl chloride auxiliary oxidizing agent according to my invention, are somewhat lower than the optimum temperatures required for oxidation of

the same heterocyclic nitrogen compound with sulfuric acid alone. Thus, whereas the optimum temperature for oxidizing quinoline to nicotinic acid by means of H_2SO_4 in the presence of a selenium catalyst lies between about 295° C. and about 315° C. and for oxidizing 3-picoline lies between about 305° C. and about 315° C., the optimum oxidation temperature when using nitrosyl chloride in its auxiliary oxidizing capacity lies in the neighborhood of 270° C. Suitable temperature ranges within which supplemental oxidizing action is exerted by nitrosyl chloride are between about 240° C. and about 300° C. At 270° C. $\pm$ about 10° C. the nitrosyl chloride exerts at least a supplementary oxidizing action in the case of all the heterocyclic nitrogen compounds as defined, and, in the case of poly substituted pyridine ring compounds such as quinoline, isoquinoline and 2-methyl-5-ethyl pyridine it exerts a promoter action as well.

The rate at which nitrosyl chloride may be introduced into the charge may vary. For maximum oxidation hastening effect however, it preferably should be introduced as rapidly as it will be completely absorbed, but slowly enough so that little if any passes out of the charge. This rate varies markedly with the stage of the reaction, larger relative proportions of nitrosyl chloride being generally utilizable in the early stages of the oxidation than near its completion. In general, I find that introduction of nitrosyl chloride should be made at a rate of at least about 1 part by weight per minute per 100 parts of heterocyclic nitrogen compound, and may be as high as about 15 parts per minute or higher, at least during the early stages of the oxidation; the rate may be decreased somewhat during the later stages if desired when and if nitrosyl chloride begins to appear in the exit gases. Usually a flow rate between about 2.5 parts and about 10 parts per minute is satisfactory. The total quantity used will vary somewhat depending on the particular heterocyclic nitrogen compound being oxidized, the temperature and the rate of introduction of $NOCl$, but in general should be sufficient to insure production of the desired supplementary or promoter action under the conditions of the oxidation. This quantity will usually lie within the range between about 125 parts and about 650 parts per 100 parts by weight of the heterocyclic nitrogen compound.

The oxidation of representative heterocyclic nitrogen bases with sulfuric acid alone proceeds according to the equations set out below (Series A) for quinoline, the picolines and 2-methyl-5-ethyl pyridine respectively,

A. Theoretical oxidation of nitrogen bases with sulfuric acid

The oxidation of the same representative heterocyclic nitrogen bases theoretically would proceed according to the equations set out below if all the oxidation were attributable to nitrosyl chloride alone (Series B),

B. Theoretical oxidation of nitrogen bases with nitrosyl chloride

One of the outstanding advantages of the present invention in addition to its inexpensiveness, is the increased rate of oxidation of heterocyclic nitrogen compounds as described, to pyridine carboxylic acids over that possible with sulfuric acid alone within the temperature range defined. The amount of this rate increase depends to some extent on the temperature, to some extent appears to be inherent in the compounds oxidized.

The increase in reaction rate induced by nitrosyl chloride over the rate of reaction using sulfuric acid alone may readily be demonstrated and measured by comparing the results obtained by bubbling nitrosyl chloride through the sulfuric acid reaction mixture, with the results obtained by bubbling an inert gas such as nitrogen through an identical oxidation mixture at the same temperature. Any loss of weight incurred in the oxidation mixture through which nitrogen is passed, will be attributable to oxidation by sulfuric acid alone, the nitrogen having no chemical effect but reproducing the physical conditions of the nitrosyl chloride-treated material by furnishing similar agitation. The loss of weight is due to loss of CO_2 , SO_2 and water vapor by volatilization as illustrated in the foregoing equations. The weight loss occurring in the oxidation mixture through which nitrosyl chloride is passed will be due to a combination of sulfuric acid oxidation and nitrosyl chloride oxidation. A comparison of weight losses at constant conversions and temperatures in the two types of oxidations gives a measure of the rate increase attributable to the nitrosyl chloride. Whether such rate increase represents merely a supplementary oxidizing effect as defined, or represents a promoter (synergistic) effect, may be ascertained by calculating the percent conversion theoretically ascribable to nitrosyl chloride on the basis of the equations set out above, adding this theoretical conversion to the conversion figure obtained using H_2SO_4 alone under comparable conditions, and comparing this total with the conversion actually obtained by the combined action of sulfuric acid and the auxiliary oxidizing agent. Positive differences are construed as evidence of promoter action; negative differences correspond to incomplete utilization of the auxiliary oxidizing agent. The degree of supplementary oxidizing effect may be ascertained by noting the improvement in percent conversion obtained when using the auxiliary oxidizing agent over the percent conversion obtained when using sulfuric acid alone under comparable conditions, all as brought out in the following specific examples which further illustrate my invention. In these examples, the figures shown for "percent conversion" are calculated from the total quantity of heterocyclic nitrogen base used up in the reaction, the resulting reaction product being essentially the acid indicated, together with small quantities of CO_2 and ammonia.

EXAMPLE 1

Quinoline was oxidized to nicotinic acid using sulfuric acid as the primary oxidizing agent and nitrosyl chloride as auxiliary oxidizing agent at about 270° C.

The apparatus used was a 4-neck flask equipped with a gas inlet tube, thermometer, thermocouple well and air condenser. The flask was heated by a quartz hemispherical mantle and temperature was controlled by a thermocouple connected to a potentiometer-controller. The entire apparatus (mantle and flask) was placed in a balance in a manner such that small weight changes in the charge were readily detectable.

In carrying out the run, the flask was charged with 2 parts of selenium as catalyst and with 900 parts of a 5.16% solution of quinoline in 95% sulfuric acid. The charge was brought rapidly to the operating temperature of 270° C. in 15 to 30 minutes, where it was maintained. Nitrosyl chloride at room temperature (about 25° C.) was then passed into the hot solution at a rate of 0.5 liter (.02 mol) per minute or 1.3 parts by weight per minute. As the oxidation progressed the weight of the charge decreased due to evolution of gaseous products of oxidation of the quinoline. Weight losses were recorded periodically and at the same time samples of the charge were analysed for conversion of the quinoline to nicotinic acid and the results recorded.

Progress of the oxidation is shown in Table 1A below.

Table 1A

[Weight loss and percent conversion of quinoline during oxidation with H₂SO₄ at 270° C. supplemented by NOCl introduced at 0.5 liter per minute]

Elapsed Time, Minutes	Weight Loss, Parts by Weight	Percent Conversion
15	70	38.5
30	125	59.3
45	160	73.8
60	181	84.0
75	189	85.0

A run carried out in a manner identical in all respects to the above except that nitrogen was passed through the charge in place of nitrosyl chloride, gave the results shown in Table 1B below.

Table 1B

[Weight loss during oxidation of quinoline with H₂SO₄ at 270° C. with introduction of N₂ at 0.5 liter per minute]

Elapsed Time, Minutes	Weight Loss, Parts
15	35
30	65
60	130
120	210
270	275
8 hrs.	315

In Table 1C below, the conversion of quinoline by sulfuric acid alone, and that, theoretically ascribable to nitrosyl chloride alone under comparable conditions as calculated from the equations in columns 3 and 4, are listed and the totals of these two effects are listed. The actual conversion found is also listed together with the improvement in conversion over H₂SO₄ alone and over the theoretical total of H₂SO₄ and nitrosyl chloride.

Table 1C

Conversion in percent of quinoline during oxidation at 270° C. with H₂SO₄ alone and with introduction of NOCl at 0.5 liter per minute]

Time, Min.	NOCl Alone, Theory	H ₂ SO ₄ Alone, Found	Total H ₂ SO ₄ + NOCl, Theory	Actual Total	Improvement over H ₂ SO ₄ alone	Improvement over Theoretical Total
15	14	7.5	21.5	38.5	+17	+17
30	28.5	15	43.5	59.3	+15.8	+15.8
45	43	22.5	65.5	73.8	+8.3	+8.3
60	57	30	87	94.0	-3.0	-3.0
75	71.5			85.0		

It will be observed from Table 1C that under the conditions of the run, NOCl exerts a significant promoter action in the early stages of the oxidation, and exerts a supplementary oxidizing action throughout the entire course of the oxidation.

EXAMPLE 2

Another oxidation of quinoline to nicotinic acid was carried out in a manner identical with that employed in Example 1 except that the oxidation temperature was 240° C., with the results, listed in Table 2A below.

Table 2A

[Weight loss and conversion of quinoline during oxidation with H₂SO₄ at 240° C. supplemented by NOCl introduced at 0.5 liter per minute]

Elapsed Time, Minutes	Weight Loss, Parts	Percent Conversion
60	42	50.7
90	42	65.7
115	42	72.0

In Table 2B below, the conversion of quinoline by sulfuric acid alone and that theoretically ascribable to nitrosyl chloride under comparable conditions as calculated from the equations in columns 3 and 4, are listed, and the totals of these two effects are listed. The actual conversion found is also listed together with improvements in conversion over H₂SO₄ alone and over the theoretical total of H₂SO₄ and nitrosyl chloride.

Table 2B

[Conversion in percent of quinoline during oxidation at 240° C. with H₂SO₄ alone and with introduction of NOCl at 0.5 liter per minute]

Time, Min.	NOCl Alone, Theory	H ₂ SO ₄ Alone, Found	Total H ₂ SO ₄ + NOCl, Theory	Actual Total	Improvement over H ₂ SO ₄ alone	Improvement over Theoretical Total
60	57	12.5	69.5	50.7	-38.2	-18.8
90	86	19	100	65.7	46.7	-34.3

It will be observed from Table 2B that under the conditions of the run NOCl exerts a supplementary oxidizing action, although no observable promoter action.

EXAMPLE 3

Another oxidation of quinoline to nicotinic acid was carried out in a manner identical with that employed in Example 1 except that the rate of introduction of NOCl gas was one liter per minute (2.6 parts by weight per minute) with the results listed in Table 3A below.

Table 3A

[Weight loss and conversion of quinoline during oxidation with H₂SO₄ at 270° C. supplemented by NOCl introduced at 1 liter per minute]

Elapsed Time, Minutes	Weight Loss, Parts	Percent Conversion
10	45	32.8
20	85	51.0
30	115	67.5
45	136	84.1
60	143	89.6
75	148	88.7

In a run carried out in a manner identical in all respects with that described above, except that nitrogen gas was introduced instead of nitrosyl chloride, the results listed in Table 3B were obtained.

Table 3B

[Weight loss during oxidation of quinoline with H₂SO₄ at 270° C. with introduction of N₂ at 1 liter per minute]

Elapsed Time, Hours	Weight Loss, Parts	Percent Conversion
12	28	16.8
2	200	60.3
5	297	77.2
8	342	79.1
12	384	82.4
23	468	82.5

In Table 3C below, the conversion of quinoline by sulfuric acid alone and that, theoretically ascribable to nitrosyl chloride alone under comparable conditions as calculated from the equations in columns 3 and 4, are listed and the totals of these two effects are listed. The

actual conversion found is also listed together with the improvement in conversion over H_2SO_4 alone and over the theoretical total of H_2SO_4 and nitrosyl chloride.

Table 3C

[Conversion in percent of quinoline during oxidation at 270° C. with H_2SO_4 alone and with introduction of NOCl at 1 liter per minute]

Time, Min.	NOCl Alone, Theory	H_2SO_4 Alone, Found	Total $H_2SO_4 + NOCl$, Theory	Actual Total	Improvement over H_2SO_4 alone	Improvement over Theoretical Total
10	19	5	24	32.8	27.8	+8.8
20	33	10	43	51.0	41.0	+3.0
30	57	15	72	67.5	52.5	-4.5
40	85	22.5	107.5	85.1	62.6	-

The data listed in Table 3C indicate that under the conditions of the run NOCl exerts a promoter action in the early stages of the oxidation and exerts a supplementary oxidizing action throughout the course of the oxidation.

EXAMPLE 4

Still another oxidation of quinoline to nicotinic acid was carried out, in a manner identical with that employed in Example 1 except that the oxidation temperature was 300° C. with the results listed in Table 4A below.

Table 4A

[Weight loss and conversion of quinoline during oxidation with H_2SO_4 at 300° C. supplemented by NOCl introduced at 0.5 liter per minute]

Elapsed Time, Minutes	Weight Loss, Parts	Percent Conversion
10	100	42.5
20	210	70.7
30	270	84.2
40	295	91.0
50	307	92.1
70	335	86.8
90	420	73.3

In a comparable run carried out at the same temperature as the above and in all respects identical with that described above except that nitrogen gas was introduced instead of nitrosyl chloride, at a rate of 1 liter per minute (instead of 0.5 liter per minute as in the above run) the results listed in Table 4B below were obtained.

Table 4B

[Weight loss during oxidation of quinoline with H_2SO_4 at 300° C. with introduction of N_2 at 1 liter per minute]

Elapsed Time, Minutes	Weight Loss, Parts	Percent Conversion
10	100	35.3
20	174	51.4
30	213	58.5
50	242	64.4
70	338	81.4

In Table 4C below, the conversion of quinoline by sulfuric acid alone and that theoretically ascribable to nitrosyl chloride alone under comparable conditions as calculated from the equations in columns 3 and 4, are listed and the totals of these two effects are listed. The actual conversion found is also listed, together with the improvement in conversion over H_2SO_4 alone and over the theoretical total of H_2SO_4 and nitrosyl chloride.

Table 4C

[Conversion in percent of quinoline during oxidation at 300° C. with H_2SO_4 alone and with introduction of NOCl at 0.5 liter per minute]

Time, Min.	NOCl Alone, Theory	H_2SO_4 Alone, Found	Total $H_2SO_4 + NOCl$, Theory	Actual Total	Improvement over H_2SO_4 alone	Improvement over Theoretical Total
10	9.5	35	44.5	42.5	7.5	-2
20	19	51.5	70.5	70.7	19.2	+0.2
30	28.5	55.5	84.0	84.2	28.7	+0.2
40	38	60	98	91	31	-7

The above table indicates that NOCl exerts a supplementary oxidizing action under the conditions of the run at 300° C. This temperature appears to be about the threshold temperature at or below which some promoter action may also be expected.

EXAMPLE 5

3-Picoline was oxidized to nicotinic acid in a manner identical in all respects to that described for quinoline under Example 1 except that 865 parts of a 6.5% solution of 3-picoline in sulfuric acid was used as the charge and that NOCl was introduced at the rate of 1 liter per minute. The results of this run are listed in Table 5A below.

Table 5A

[Weight loss and percent conversion of 3-picoline during oxidation with H_2SO_4 at 270° C. supplemented by NOCl introduced at 1 liter per minute]

Elapsed Time, Minutes	Weight Loss, Parts	Percent Conversion
15	-7 (gain)	11.7
30	-10	22.7
60	-10	43.8

In a run carried out in a manner identical in all respects to that described above except that nitrogen was introduced instead of nitrosyl chloride, the results listed in Table 5B below were obtained.

Table 5B

[Weight loss and percent conversion of 3-picoline during oxidation with H_2SO_4 at 270° C. with introduction of N_2 at 1 liter per minute]

Elapsed Time, Hours	Weight Loss, Parts	Percent Conversion
1	65	9.9
3	140	10.0
6½	240	16.9
15	440	37.3

In Table 5C below, the conversion of 3-picoline by sulfuric acid alone, and that theoretically ascribable to nitrosyl chloride under comparable conditions as calculated from the equations in columns 3 and 4, are listed and the totals of these two effects are listed. The actual conversions found in each case are also listed together with improvements in conversion over H_2SO_4 alone and over the theoretical total of H_2SO_4 and nitrosyl chloride.

Table 5C

[Conversion in percent of 3-picoline during oxidation at 270° C. with H_2SO_4 alone and with introduction of NOCl at 1 liter per minute]

Time, Min.	NOCl Alone, Theory	H_2SO_4 Alone, Found	Total $H_2SO_4 + NOCl$, Theory	Actual Total	Improvement over H_2SO_4 alone	Improvement over Theoretical Total
15	49	1	50	11.7	10.7	-38.3
30	97.5	2	99.5	22.7	20.7	-76.8
60		3.5		43.8	40.3	-

The above data indicate that, under the conditions of the run NOCl exerts a supplementary oxidizing action on the oxidation of 3-picoline, but no promoter action.

EXAMPLE 6

3-Picoline was oxidized to nicotinic acid in a manner identical in all respects to that described for quinoline under Example 1 except that 875 parts of a 6.5% solution of 3-picoline in sulfuric acid was used as the charge and the oxidation was carried out at 300° C. and NOCl was introduced at 1 liter per minute. The results of this run are listed in Table 6A below.

9
Table 6A

[Weight loss and percent conversion of 3-picoline during oxidation with H_2SO_4 at 300° C. supplemented by NOCl introduced at 1 liter per minute]

Elapsed Time, Minutes	Weight Loss, Parts	Percent Conversion
10	35	11.8
20	65	27.0
30	90	50.1
45	110	77.9
60	130	93.7
90	230	100

In a run carried out in a manner identical in all respects with that described above except that nitrogen gas was introduced instead of nitrosyl chloride, the results listed in Table 6B below were obtained.

Table 6B

[Weight loss and percent conversion during oxidation of 3-picoline with H_2SO_4 at 300° C. with introduction of N_2 at 1 liter per minute]

Elapsed Time, Hours	Weight Loss, Parts	Percent Conversion
1/2	95	7.6
2	215	24.6
6	440	50.3
9	565	57.6

In Table 6C below, the conversion of 3-picoline by sulfuric acid alone, and that theoretically ascribable to nitrosyl chloride alone under comparable conditions, as calculated from the equations in columns 3 and 4 are listed and the totals of these two effects are listed. The actual conversion found is also listed together with the improvements in conversion over H_2SO_4 alone and over the theoretical total of H_2SO_4 and nitrosyl chloride.

Table 6C

[Conversion, in percent, of 3-picoline during oxidation at 300° C. with H_2SO_4 alone and with introduction of NOCl at 1 liter per minute]

Time, Min.	NOCl Alone, Theory	H_2SO_4 Alone, Found	Total $H_2SO_4 + NOCl$, Theory	Actual Total	Improvement over H_2SO_4 alone	Improvement over Theoretical Total
10	32.5	2	34.5	11.8	9.8	-22.7
20	65	4	69	27.0	23.0	-42
30	97.5	6	103.5	50.1	44.1	-

The above table indicates that under the conditions of the run, NOCl exerts an appreciable supplementary oxidizing effect on the H_2SO_4 oxidation of 3-picoline but no promoter action.

EXAMPLE 7

Isoquinoline was oxidized to cinchomeronic acid in a manner identical in all respects to that described for quinoline under Example 1 except that 890 parts of a 5.15% solution of isoquinoline in sulfuric acid was used as the charge and the NOCl was introduced at the rate of 1 liter per minute. Results of this run are given in Table 7A below.

Table 7A

[Weight loss and percent conversion of isoquinoline during oxidation with H_2SO_4 at 270° C. supplemented by NOCl introduced at 1 liter per minute]

Elapsed Time, Minutes	Weight Loss, Parts	Percent Conversion
10	45	36.2
20	100	58.9
30	155	81.7
45	195	94.9
60	200	95.4

In a run carried out in a manner identical in all respects to that described above except that nitrogen was introduced instead of nitrosyl chloride, the results listed in Table 7B below were obtained.

10
Table 7B

[Weight loss and percent conversion of isoquinoline during oxidation with H_2SO_4 at 270° C. with introduction of N_2 at 1 liter per minute]

Elapsed Time, Hours	Weight, Loss, Parts	Percent Conversion
1/2	120	35.3
1	270	73.6
2	345	85.8
3	360	87.5
5	380	89.9

In Table 7C below, the conversion of isoquinoline by sulfuric acid alone and that theoretically ascribable to nitrosyl chloride alone as calculated from the equations in columns 3 and 4, are listed and the totals of these two effects are listed. The actual conversions found are also listed together with improvements in conversions over H_2SO_4 alone and over the theoretical total of H_2SO_4 and nitrosyl chloride.

Table 7C

[Conversion, in percent, of isoquinoline during oxidation at 270° C. with H_2SO_4 alone and with introduction of NOCl at 1 liter per minute]

Time, Min.	NOCl Alone, Theory	H_2SO_4 Found	Total $H_2SO_4 + NOCl$, Theory	Actual Total	Improvement over H_2SO_4 alone	Improvement over Theoretical Total
10	19	12	31	36.2	24.2	+5.2
20	38	24	62	58.9	34.9	-3.1
30	57	36	93	81.7	45.7	-11.3

The above table indicates that under the conditions of the run NOCl exerts a considerable supplementary oxidizing action, and some promoter action on the H_2SO_4 oxidation of isoquinoline.

EXAMPLE 8

2-methyl-5-ethyl pyridine (aldehyde collidine) was oxidized to nicotinic acid in a manner identical in all respects to that described for quinoline in Example 1, except that 875 parts of a 5% solution of 2-methyl-5-ethyl pyridine in sulfuric acid was used as the charge. Results of this run are given in Table 8A below.

Table 8A

[Weight loss and percent conversion of 2-methyl-5-ethyl pyridine during oxidation with H_2SO_4 at 270° C. supplemented by NOCl introduced at 0.5 liter per minute]

Elapsed Time, Minutes	Weight Loss, Parts	Percent Conversion
10	35	25.1
25	40	36.1
45	45	54.8
75	50	81.8
120	60	100

In a run carried out in a manner identical in all respects to that described above except that nitrogen was introduced instead of nitrosyl chloride, the results listed in Table 8B below were obtained.

Table 8B

[Weight loss and percent conversion during oxidation of 2-methyl-5-ethyl pyridine with H_2SO_4 at 270° C. with introduction of N_2 at 0.5 liter per minute]

Elapsed Time, Hours	Weight, Loss, Parts	Percent Conversion
1	80	28.8
3	185	51.6
5	255	75.4
9	355	94.0

In Table 8C below, the conversion of 2-methyl-5-ethyl pyridine by sulfuric acid alone, and that theoretically ascribable to nitrosyl chloride alone as calculated from the equations in columns 3 and 4, are listed and the totals of these two effects are listed. The actual conversions found are also listed, together with improvements in

11

conversions over H_2SO_4 alone and over the theoretical total of H_2SO_4 and nitrosyl chloride.

Table 8C

[Conversion, in percent, of 2-methyl-5-ethyl pyridine during oxidation at 270° C. with H_2SO_4 alone and with introduction of NOCl at 0.5 liter per minute]

Time, Min.	NOCl Alone, Theory	H_2SO_4 Alone, Found	Total $H_2SO_4 + NOCl$, Theory	Actual Total	Improvement over H_2SO_4 alone	Improvement over Theoretical Total
10-----	9	5	14	25.1	20.1	+11.1
25-----	23	12	35	36.1	24.1	+1.1
45-----	41	21.5	62.5	54.8	33.3	-7.7

The above table indicates that under the conditions of the run, NOCl exerts a considerable supplementary oxidizing action and appreciable promoter action on the H_2SO_4 oxidation of 2-methyl-5-ethyl pyridine.

While the above describes the preferred embodiments of my invention, it will be understood that departures of may be made therefrom within the scope of the specification and claims.

I claim:

1. A process for preparing pyridine carboxylic acids which comprises subjecting a heterocyclic nitrogen compound containing a single pyridine nucleus, selected from the group consisting of quinoline, alkyl quinolines, isoquinoline, alkyl isoquinolines, 5- and 8-hydroxy quinolines, 5- and 8-nitroquinolines and the alkyl pyridines, dissolved in concentrated sulfuric acid to the action of nitrosyl chloride at a temperature between about 240° C. and about 300° C. in the presence of between about 0.5% and about 25% by weight, based on the weight of the nitrogen compound of a selenium-containing catalyst to convert the heterocyclic nitrogen compound to a pyridine carboxylic acid the quantity of sulfuric acid used being sufficient to provide at least a slight excess thereof over that required to form the nitrogen base sulfate, and to maintain such an excess during the oxidation reaction.

2. The process according to claim 1 wherein the heterocyclic nitrogen compound is isoquinoline.

3. A process for preparing pyridine carboxylic acids which comprises subjecting a sulfate of a heterocyclic nitrogen compound containing a single pyridine nucleus, selected from the group consisting of quinoline, alkyl quinolines, isoquinoline, alkyl isoquinolines, 5- and 8-hydroxy quinolines, 5- and 8-nitroquinolines and the alkyl pyridines, dissolved in concentrated sulfuric acid to the action of nitrosyl chloride at a temperature between about 240° C. and about 300° C. in the presence of between about 0.5% and about 25% by weight, based on the weight of the nitrogen compound, of a selenium-containing catalyst to convert the heterocyclic nitrogen compound to a pyridine carboxylic acid the quantity of sulfuric acid used being sufficient to provide at least a slight excess thereof over that required to form the nitrogen base sulfate, and to maintain such an excess during the oxidation reaction.

4. A process for preparing pyridine carboxylic acids which comprises subjecting a heterocyclic nitrogen compound containing a single pyridine nucleus, selected from the group consisting of quinoline, alkyl quinolines, isoquinoline, alkyl isoquinolines, 5- and 8-hydroxy quinolines, 5- and 8-nitroquinolines and the alkyl pyridines, dissolved in concentrated sulfuric acid to the action of nitrosyl chloride at a temperature between about 240° C. and about 300° C. in the presence of between about 0.5% and about 25% by weight, based on the weight of the nitrogen compound of a selenium-containing catalyst for a period between about 30 minutes and about 2 hours the quantity of sulfuric acid used being sufficient to provide

12

at least a slight excess thereof over that required to form the nitrogen base sulfate, and to maintain such an excess during the oxidation reaction.

5. The process of claim 1 wherein the heterocyclic nitrogen compound is quinoline.

6. The process of claim 1 wherein the heterocyclic nitrogen compound is 3-picoline.

7. The process of claim 1 wherein the heterocyclic nitrogen compound is 2-methyl-5-ethyl pyridine.

8. In a process for accelerating the sulfuric acid oxidation of heterocyclic nitrogen compounds containing a single pyridine nucleus selected from the group consisting of quinoline, alkyl quinolines, isoquinoline, alkyl isoquinolines, 5- and 8-hydroxy quinolines, 5- and 8-nitroquinolines and the alkyl pyridines, the steps which comprise dissolving said heterocyclic nitrogen compound and between about 0.5% and about 25% by weight, based on the weight of the nitrogen compound a selenium-containing catalyst in concentrated sulfuric acid, and 10 subjecting the resulting solution in the liquid phase to the action of gaseous nitrosyl chloride at temperatures between about 240° C. and about 300° C. to effect conversion of heterocyclic nitrogen base to pyridine carboxylic acid the quantity of sulfuric acid used being sufficient to provide at least a slight excess thereof over that required to form the nitrogen base sulfate, and to maintain such an excess during the oxidation reaction.

9. A process for producing an acceleration of the selenium catalyzed sulfuric acid oxidation of quinoline, 30 greater than that theoretically ascribable to the combined action of the oxidizing agents used, which comprises subjecting said quinoline, dissolved in concentrated sulfuric acid, and in the presence of between about 0.5% and about 25% by weight, based on the weight of the quinoline, of a selenium-containing catalyst, to the action of nitrosyl chloride at a temperature of about 270° C. for a period of at least about 30 minutes, the quantity of sulfuric acid used being sufficient to provide at least a slight excess thereof over that required to form quinoline 35 sulfate and to maintain such an excess during the oxidation reaction.

10. A process for producing an acceleration of the selenium catalyzed sulfuric acid oxidation of isoquinoline, greater than that theoretically ascribable to the combined action of the oxidizing agents used, which comprises subjecting said isoquinoline, dissolved in concentrated sulfuric acid, and in the presence of between about 0.5% and about 25% by weight, based on the weight of the isoquinoline, of a selenium-containing catalyst, to the action of nitrosyl chloride at a temperature of about 270° C. for a period of at least about 30 minutes, the quantity of sulfuric acid used being sufficient to provide at least a slight excess thereof over that required to form isoquinoline sulfate and to maintain such an excess during the oxidation reaction.

11. A process for producing an acceleration of the selenium catalyzed sulfuric acid oxidation of 2-methyl-5-ethylpyridine, greater than that theoretically ascribable to the combined action of the oxidizing agents used, which 60 comprises subjecting said 2-methyl-5-ethylpyridine, dissolved in concentrated sulfuric acid, and in the presence of between about 0.5% and about 25% by weight, based on the weight of the 2-methyl-5-ethylpyridine, of a selenium-containing catalyst, to the action of nitrosyl chloride at a temperature of about 270° C. for a period of at least about 30 minutes, the quantity of sulfuric acid used being sufficient to provide at least a slight excess thereof over that required to form 2-methyl-5-ethylpyridine sulfate and to maintain such an excess during the oxidation reaction.
